UNITED STATES PATENT OFFICE.

CASSIUS M. MAXSON, OF ALLENTEWON, NEW YORK.

NUTMEG-GRATER.

SPECIFICATION forming part of Letters Patent No. 435,235, dated August 26, 1890.

Application filed January 23, 1890. Serial No. 337,832. (No model.)

To all whom it may concern:

Be it known that I, CASSIUS M. MAXSON, of Allentown, in the county of Allegany and State of New York, have invented a new and

5 Improved Nutmeg-Grater, of which the following is a full, clear, and exact description.

Reference is to be had to the accompanying drawings, forming a part of this specification, in which similar letters of reference indicate 10 corresponding parts in all the figures.

Figure 1 is a side elevation of my new and improved nutmeg-grater. Fig. 2 is a longitudinal sectional elevation of the same. Fig. 3 is a transverse sectional view on line xx of 15 Fig. 2. Fig. 4 is a similar view on line yy of Fig. 2, and Fig. 5 is a perspective view of the rotating grating-disk.

The invention will first be described in connection with the drawings, and then pointed 20 out in the claims.

A represents a hollow body, preferably in cylindrical form, made of wood, metal, hard rubber, glass, porcelain, or other suitable material. One end is closed by a cap B, perforated at bb , and preferably screwed upon the body A, or otherwise tightly fastened thereto. The opposite end is closed by the cap C, screwed or otherwise fastened to the body A, and in this is formed the bearing d for the 25 small crank-shaft D. To the inner end of the said crank-shaft is secured the grinding-disk E.

F is the opposite grinding-disk held to move longitudinally in the body A and acted upon 30 by the coiled spring G, which acts between the said grinding-disk and the cap B, and presses the teeth of the disk in contact with the nutmeg N, held between the two grinding-disks E and F.

40 The disk E is formed with radial rows of teeth $ee'e^2$. The teeth e , at each side of the center, are formed alike and have an inverted-V shape, their edges thus ranging transversely to the direction of the row of teeth. The 45 teeth e' are beveled rearwardly from their front vertical end, presenting a cutting-edge at said front end. The teeth e^2 are similar to the teeth e' , but oppositely beveled. The teeth e cut grooves in the nutmeg and the

teeth $e'e^2$ shave off the ridges thus formed. 50 The teeth f , f' , and f^2 , of the disk F, are like the teeth $ee'e^2$ of the disk E and need no further description.

The disk F is guided in its movement in the body A by the ribs gg , formed on the body A, and said disk is formed with grooved arms or extensions hh , which embrace the said ribs and prevent the said disk from turning out of place. Said disk is also formed with openings i , through which the grated 60 nutmeg may pass to the cap B through the openings b of which the fine nutmeg may be shaken as pepper is shaken from a common pepper-box.

nn represent stops on the ribs g to limit 65 the inward movement of the grinding-disk F.

In use the cap B, spring G, and grinding-disk F are to be removed and a nutmeg or other substance to be ground placed in the body on the grinding-disk E. The said parts 70 are then to be replaced. The spring G being of considerable tension will press the disk F forcibly against the nutmeg or other substance, which in turn will press the nutmeg or other substance against the grinding-plate 75 E, so that when the latter is revolved the teeth of the grinding-plates will grind off the nutmeg, or grind or pulverize the substance acted upon by the disks. The nutmeg or other substance will be ground in quantities 80 as used and shaken from the device as above stated.

Having thus described my invention, what I claim as new, and desire to secure by Letters Patent, is—

1. In a grater, the combination, with a hollow body, of a removable perforated cap at one end, a spring-supported grating-disk fitted within the body at said end and formed with openings or perforations, and a crank fitted 90 in the opposite end and carrying a second grating-disk, the perforated disk and perforated end cap forming the exit for grated material, substantially as described.

2. The grinding-disk E, formed with radial 95 rows of teeth $ee'e^2$, each tooth e being of inverted-V shape and ranging transversely to the direction of its row of teeth, and the teeth

e' e² being beveled rearwardly from their front vertical ends, forming cutting-edges at said front ends, substantially as described.

3. The hollow body A, formed with ribs *g* and closed at one end with a cap C, having the bearing *d*, and at the other with the perforated cap B, in combination with the crank-shaft D, grinding-disk E, attached thereto,

the opposite longitudinally-movable grinding-disk F, and the spring G, arranged to press constantly upon the disk F, substantially as described.

CASSIUS M. MAXSON.
